UNITED STATES PATENT OFFICE.

GEORGE E. SHIRLEY, OF GALENA, KANSAS.

DESIGN FOR A FLUE-CLEANER BLADE.

SPECIFICATION forming part of Design No. 35,541, dated December 31, 1901.

Application filed July 11, 1901. Serial No. 67,932. Term of patent 7 years.

To all whom it may concern:

Be it known that I, GEORGE E. SHIRLEY, a citizen of the United States, residing at Galena, in the county of Cherokee and State of Kansas, have invented and produced a new and original Design for a Flue-Cleaner Blade, of which the following is a specification, reference being had to the accompanying drawings, forming a part thereof.

Figure 1 represents a perspective view of my design. Fig. 2 represents a similar view taken from a different point. Fig. 3 represents an end elevation.

My design for a flue-cleaner blade comprises a quadrant-shaped plate 1, along one straight edge of which is disposed a plate 2 at right angles to the quadrant 1. This plate is provided with a hole 3. Along one edge

of the plate 2 is a plate 4, disposed at right angles to plate 2 and having its outer edge in line with the other straight edge of the quadrant 1. Intermediate of the plate 2 is a triangular-shaped plate 5, connecting the quadrant 1 and plate 2. The quadrant-shaped plate is provided with a curved edge 6, as shown.

What I claim as new, and desire to secure by Letters Patent, is—

The design for a flue-cleaner blade, substantially as shown and described.

In testimony whereof I have affixed my signature in the presence of two witnesses.

GEORGE E. SHIRLEY.
